UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPOGRAPHICAL COMPOSING-MACHINE.

1,212,542.

Specification of Letters Patent. Patented Jan. 16, 1917.

Application filed March 29, 1915. Serial No. 17,583.

To all whom it may concern:

Be it known that I, CARL MUEHLEISEN, a citizen of the United States of America, residing at Chausseestrasse 23, Berlin N. 4, 5 in the Empire of Germany, have invented new and useful Improvements in Typographical Composing-Machines, of which the following is a specification.

This invention relates to typographical 10 composing machines, especially machines such as those known under the trade mark "Linotype," in which matrices, stored in magazines, are released from the latter in order of composition, and, after presentation to a casting mold for the production 15 of casts therefrom, are returned to the said magazines.

The present invention deals particularly 20 with such machines as are provided with a plurality of magazines and a single assembler plate, and in which, as is already known, the magazines are pivotally mounted so as to be adjustable relatively to the assembler plate, or the assembler plate is thus mounted 25 and adjustable relatively to the magazines, so that, at the will of the operator, matrices can be assembled from any of the magazines, according to the font to be employed. In 30 machines of the just-named arrangement, as heretofore constructed, difficulty has been experienced through the track or path followed by the matrices on leaving the magazines and entering the assembler plate entrance, varying for different magazines 35 brought into use, and the object of the present invention is to provide means for overcoming or minimizing that difficulty, said means comprising a member in pivotal relationship to the assembler plate entrance, 40 and so arranged and controlled that it will occupy practically the same position relatively to each of the magazines when that magazine is itself in operative relationship to the assembler plate entrance.

45 The invention will now be described by reference to the accompanying drawings, which represent three different constructional forms of the said invention.

In these drawings: Figure 1 is a vertical 50 sectional view of sufficient of a typographical machine to illustrate the embodiment therein of one of such constructional forms, the machine represented being one provided with two pivotally-mounted magazines of 55 which this figure shows the lower one to be

in operative position; Fig. 2 is a view corresponding to the upper part of Fig. 1, but with the upper magazine in operative position; Fig. 2^a is a detail view, and Fig. 3 is a vertical sectional view of a constructional form of the invention embodied in a machine having four stationary magazines and a pivoted assembler plate. 60

Like reference numerals are used for indicating like or corresponding parts 65 throughout the several figures of the drawings.

In the constructional form according to Figs. 1 and 2, the two magazines 1, 2, are capable of being moved angularly about a 70 pivot so that each of them can be brought into and out of operative relationship to the assembler plate 3; the just-mentioned pivot is not shown in the drawings as it is an arrangement which constitutes no part of the 75 present invention and moreover is already well known in the art.

As before-mentioned, Fig. 1 represents the lower magazine in operative position, and Fig. 2 the upper magazine, and it will be 80 seen by reference to these figures, that whereas the angle of inclination of the upper magazine 1 and of the assembler plate entrance 4 is practically the same when these two organs are in operative relationship as 85 in Fig. 2, the angle of inclination of the lower magazine 2, when the latter is in operative position, as shown in Fig. 1, differs appreciably from that of the assembler plate entrance. 90

In order to satisfactorily guide the matrices 5 into the assembler plate entrance from whichever of the magazines 1, 2, is, at the time, in operation, there is provided a horizontal guide bar or switch 6 extending 95 throughout the length of, and pivoted by a rod 7 to, the said entrance so that that bar virtually constitutes a hinged portion of the back plate of that entrance, capable of being turned from the position in which it 100 is shown in Fig. 1 to the position in which it is shown in Fig. 2 and vice versa.

The switch 6 has fast to or integral with it, an arm 8 to which is pivoted the upper end of a rod 9 whose lower end is pivotally 105 connected to a slide 10 free to move vertically up and down in a guide slot 11 in the fixed frame 12 of the machine, to which frame the assembler plate 3 is secured in well-known manner. On the front end of 110

the slide 10 is mounted an anti-friction roller 13 constantly held in contact with an edge cam 14 by a tension spring 15 attached at its respectively opposite ends to the rod 9 and frame 12. The cam 14 is in rigid connection with a spur wheel 16 capable of rotating about a fixed stud 17 and meshing with a spur pinion 18 fast on a shaft 19 by the rotation of which latter is effected the adjustment of the magazines 1, 2, into and out of operative relationship to the assembler plate entrance 4. The shaft 19 is rotated by means of a crank handle 20 and a halt rotation of the cam 14 suffices to move the magazines 1, 2, from one terminal position to the other. The means for transmitting motion from the shaft 19 to the magazines, may be of any suitable construction, that shown in the present instance comprising an upright shaft 19^a connected at its lower end by bevel gearing 19^b to the shaft 19, and connected at its upper end by bevel gearing 19^c to a transverse rock shaft 19^d, having fast thereon one or more cams 19^e arranged in engagement with the magazines or their supporting frame. The cam 14 is so shaped that, during the movement of the magazines into and out of their respective operative positions, the switch 6 is turned about its pivot 7 in such manner that when the said operative position is arrived at, the matrix-guiding surface of the switch will have the same or practically the same angle of inclination as has the magazine then in such operative position, as shown in Figs. 1 and 2. For automatically adjusting the escapement reeds 21 to correspond with the altered condition established by the bringing into operative position of the respective magazines 1, 2, the comb plate 22 in which these reeds are guided at their upper ends, is automatically moved in fore-and-aft direction whenever an operative change of magazine is made. For attaining this result, the comb plate 22 is secured to a lever or frame 23 capable of rocking about a stationary pivot 24, and having pivoted to it the upper end of a link 25 whose lower end is pivoted to the horizontal arm of a bell-crank lever 26. This lever is free to turn about a pivot 27 fast to the machine frame 12, and has an anti-friction roller 28 pivoted in or to its vertical arm, a tension spring 29 serving to hold the said roller constantly in contact with a face cam 30. The cam 30 is integral with the edge cam 14, or, in other words, it and the said edge cam are different operative surfaces of one and the same body. By the foregoing arrangement, the act of turning the shaft for effecting an operative change of magazine, automatically effects, simultaneously therewith, the adjustment of the switch 6 and of the escapement reeds 21, so that when such operative change is completed, these devices will occupy their proper

positions relatively to the magazine 1 or 2 and the escapements 31 with which they are respectively to coöperate. Thus when the magazine shifting mechanism is operated to change from the lower to the upper magazine, the initial operation of said means brings the low surface of the face cam 30 opposite the roller 28 on the pivoted lever 26, which then under the influence of the spring 29 through the connections described moves the escapement reeds 21 forwardly toward the assembler entrance and clear of the path of movement of the magazines, as shown by dotted lines in Fig. 1. During the continued operation of the magazine shifting means, the roller 28 continues to track upon the lower surface of the cam 30 until the upper magazine is brought into operative position, when the raised surface of the cam will reengage the roller and cause the lever 26 to move the escapement reeds again rearwardly into position to engage and actuate the escapement levers as shown in Fig. 2.

In the constructional form illustrated in Fig. 3, wherein, as an example, four magazines 1, 2, 1^a and 2^a are shown, and wherein, for bringing any one of these magazines into operation, the assembler plate 3 is, as shown in my co-pending application Serial No. 15,317, swung about a pivotal axis situated at or near its lower end, the arm 8 of the switch 6 is provided with an anti-friction roller 32 which, during such swinging movement of the assembler plate 3, travels over a stationary cam track 33, which is eccentric to the aforesaid pivotal axis or of such contour as will cause the switch, when in register with any one of the magazines, to assume the angle best suited to bridge the gap between that magazine and the adjacent top edge of the assembler entrance. In the figure now under review, the assembler plate 3 is shown in full and chain lines in operative relationship to respectively the magazines 2^a and 1.

Having described my invention, I declare that what I claim and desire to secure by Letters Patent is:—

1. In a typographical composing machine, the combination with a plurality of magazines and an assembler plate one of which is movable relatively to the other so that the assembler plate can receive matrices from any of the magazines, of a switch intervening the magazines and assembler plate and means operative to automatically adjust the switch angularly to approximately the plane of each selected magazine.

2. In a typographical composing machine, the combination with a plurality of magazines and an assembler plate, means for adjusting the former relatively to the latter so that the assembler plate can receive matrices from any of the magazines, of a switch

intervening the magazines and assembler plate, and automatic means operative to adjust the switch to approximately the plane of each selected magazine during the adjustment of the magazines.

3. In a typographical composing machine, the combination with a plurality of magazines, an assembler plate receiving matrices from the respective magazines, and manual means operative to alternatively move each of the magazines into operative relationship to the assembler plate, of a switch intervening the magazines and assembler plate, and means operatively connecting the switch to the aforesaid manual means whereby it is adjusted to approximately the plane of each magazine as it is brought into operative relationship to the assembler plate.

4. In a typographical composing machine, the combination with a plurality of magazines, a bank of escapements on each magazine, escapement reeds adapted to actuate the said escapements, an assembler plate receiving matrices from the respective magazines, and manual means operative to alternatively move each magazine into operative relationship to the assembler plate, of a switch intervening the magazines and assembler plate, means operatively connecting the switch to the aforesaid manual means whereby it is adjustable to approximately the plane of each magazine as it is brought into operative relationship to the assembler plate, and means operatively connected to the said manual means, operative to adjust the escapement reeds to the respective banks of escapements to be actuated by them.

5. In a typographical composing machine, the combination with a plurality of magazines, a bank of escapements on each magazine, escapement reeds adapted to actuate the said escapements, an assembler plate receiving matrices from the respective magazines, and manual means operative to alternatively move each magazine into operative relationship to the assembler plate, of a switch intervening the magazines and assembler plate, and a cam operatively connected to the aforesaid manual means whereby the switch is adjusted to approximately the plane of each magazine as it is brought into operative position.

6. In a typographical composing machine, the combination with a plurality of magazines, a bank of escapements on each magazine, escapement reeds adapted to actuate

the said escapements, an assembler plate receiving matrices from the respective magazines, and manual means operative to alternatively move each magazine into operative relationship to the assembler plate, of a switch intervening the magazines and assembler plate, and a cam operatively connected to the aforesaid manual means operative to automatically adjust the escapement reeds to the respective banks of escapements to be actuated by them.

7. An assembler plate for linotype machines provided at its entrance mouth with a bar or switch which is adjustable to different angular operative positions, for the purpose described.

8. In a typographical machine, the combination of a plurality of magazines, an assembler plate adapted to coöperate with one or another of the magazines, and provided at its entrance mouth with an adjustable bar or switch, and automatic means for adjusting the switch to different angular operative positions to correspond to one or another of the magazines.

9. In a typographical machine, the combination of a plurality of magazines and an assembler plate to receive matrices therefrom, one of said parts being pivotally mounted so as to be moved relatively to the other to locate the assembler plate in registration with one or another of the magazines, with additional guiding means interposed between the assembler plate and the magazines to insure the proper delivery of the matrices from the latter to the former in any of the different positions of the pivoted part.

10. In a typographical machine, the combination of a fixed assembling throat, a plurality of magazines each provided with escapements and pivotally mounted so that one or another may be brought into registration with the assembling throat, escapement actuating devices, and automatic means for moving the escapement actuating devices toward and from the assembling throat as the magazines are moved, for the purpose described.

In witness whereof I have hereunto set my hand in the presence of two witnesses.

CARL MUEHLEISEN.
